Oscar R. Schmidt

ATTORNEY

UNITED STATES PATENT OFFICE.

EDWIN D. BELKNAP, OF EAST ORANGE, NEW JERSEY.

STRUCTURE FOR USE IN MAKING STENCIL-CARDS.

1,256,510.

Specification of Letters Patent. Patented Feb. 19, 1918.

Application filed July 6, 1917. Serial No. 179,101.

To all whom it may concern:

Be it known that I, EDWIN D. BELKNAP, a citizen of the United States of America, residing at East Orange, county of Essex, 5 State of New Jersey, have invented certain new and useful Improvements in Structures for Use in Making Stencil-Cards, of which the following is a specification.

My invention relates to the manufacture 10 of stencil cards for use in addressing machines and for similar purposes, and is particularly designed to facilitate the manufacture of such stencil cards as are described in my prior Patent No. 1,198,691, issued September 19, 1916, with particular reference to the structure composed of the parts marked 15 5 and 6 in the drawing of said patent. The stencil card there shown, as usually made, is so flexible as to be a little difficult of handling in typewriting machines in which the cards are formed into stencils. Furthermore 20 the stencilizable material which is of the general nature described in U. S. Patent No. 1,101,242, granted to Frank D. Belknap, June 23, 1914, is so delicate and translucent 25 that the portions of its filling displaced by the action of the type in the typewriting machine in the formation of the stencil card produce such a slight visible change that it is 30 difficult to read the characters so formed unless some special means is employed for rendering them specially legible. My present invention overcomes these difficulties in a simple manner and secures other advantages hereinafter to be more fully set out.

The best form of apparatus at present known to me embodying my invention is illustrated in the accompanying sheet of drawings in which—

40 Figure 1 is a face view of the completed structure.

Fig. 2 is a detail view of one of the main elements, and

45 Fig. 3 is a detail view of the other of the main elements of the combination.

Throughout the drawings like reference figures indicate like parts.

1, is a strip of flexible material which I will call the frame strip, it being cut away 50 with a series of uniform rectangular openings 2, 2, so that the strip so cut forms in substance a connected series of frames for the stencil cards to be formed. Usually these strips 1, are formed of some tough 55 flexible paper or thin flexible cardboard. 3, represents the stencilizable sheet which is

pasted or otherwise caused to firmly adhere to the back of the perforated strip 1, and substantially coextensive therewith. This material 3, is usually Yoshino paper treated 60 in substantially the manner set out in the above mentioned patent to Frank D. Belknap, so that the coating or filling material may be displaced by the blow of the typewriting machine sufficiently to permit printing ink to pass therethrough and create a 65 stencilizing action.

4, is a backing strip usually of heavier material such as heavy cardboard which is, however, still sufficiently flexible to be easily 70 run through the typewriting machine. This backing 4, is opaque, (while the material 3, is translucent to a degree) and is substantially coextensive with the strip 1, being fastened to said strip 1, preferably at one end 75 only as at the end 6.

Preferably the backing strip 4, is also provided with sets of parallel registration lines 5, 5, which may be connected by vertical lines 7, 7, at their ends, which sets of registration lines are arranged to register with the rectangular openings 2, 2, as indicated in dotted lines in Fig. 1. These lines are marked in black ink or other color sufficiently pronounced to show through the 85 translucent stencilizable material 3.

In using my invention the completed structure shown in Fig. 1 is fed through the typewriting machine beginning at the end 6, with the stencilizable material 3, presented 90 to the face of the operating type. The operator can then easily preserve the correct alignment of the written characters on the registration lines 5, 5, and being guided by the vertical lines 7, 7, can preserve the 95 proper border between the ends of the written lines and the edges of the frame strip. After the entire strip of cards is written they are separated one from another by cutting them apart along the lines 8, 8, 100 and they are then ready for use in the structure shown in my above mentioned Patent No. 1,198,691.

A new frame strip with attached sheet of stencilizable material may then be fastened to the backing strip and the 105 operation repeated over and over again until the backing strip finally is completely worn out, which does not occur until after some hundreds of repetitions of the operation.

The advantages of my invention comprise 110 the convenient handling of the cards in the typewriting machine which conduces to

rapid operation, the accurate spacing of the written matter and the ease with which the stenciled characters may be read against the background of the opaque strip so as to 5 promptly disclose any errors made in the writing and avoid duplication or omission of any names in the list being copied. It is evident that various changes could be made in the details of construction above described 10 without departing from the principle of the invention here disclosed and that certain sub combinations of elements described could be utilized to good advantage without necessarily employing others.

15 Having described my invention, I claim:

As an article of manufacture, a tape-like strip of material flexible enough to be con-

veniently run through a typewriting machine but stiff enough to serve as a frame for stencil card blanks, said strip having a series 20 of rectangular cutout portions and transverse lines for division between said cutout portions and a sheet of stencilizable paper covering said cutout portions and fastened to the back of the strip, whereby a strip of 25 stencilizable blanks is formed which may be conveniently converted into stencils in a typewriting machine, and any cards so written can be severed from the remainder of the strip for use as separate stencil cards. 30

EDWIN D. BELKNAP.
